FIG. 1.

UNITED STATES PATENT OFFICE

2,402,182

ROTOR

Leo Rosen, Arlington, Va.

Application January 7, 1943, Serial No. 471,637

17 Claims. (Cl. 35—4)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to switching mechanisms and more particularly to cryptographic switching devices.

A primary object of this invention is the provision of a system of cryptographic commutators, or similar devices, subject to less wear and switching problems and therefore capable of greater accuracy. Other objects and advantages of this invention will appear as this description proceeds.

Wear has long been a serious problem in cryptographic commutating systems because as a result of the wear the points make unsatisfactory contact, particularly when the insulating material of the switch is exposed to the pressure of passing contacts.

The fundamental principle of this invention provides for removing the tension between the contacts during the period the contacts are rotated. Means are provided to rotate the commutators and to simultaneously remove the tension between the contacts.

In the drawing:

Fig. 1 illustrates a cryptographic system embodying the invention.

Fig. 2 illustrates on an enlarged scale a portion of a switching member of the system.

Fig. 3 illustrates a portion of a modified form of switching element.

Fig. 4 illustrates still another form of my invention.

Fig. 5 is a side view of the modification shown in Fig. 4.

In the drawing there is disclosed one embodiment of my invention comprising a cryptographic machine employing a plurality of circuits and of a type similar to that disclosed in U. S. Patent No. 2,139,676 to William F. Friedman. Each of the circuits of my machine is controlled at one end by a key, similar to a typewriter key, each of said keys being denominated by the reference character A, B, etc. These keys are mounted in a manner similar to those of a typewriter and include a universal bar UVB and a spacer bar SB. Corresponding to keys A, B, etc., the machine includes reproducing devices indicated as AA, BB, etc., which, when energized, reproduce a selected character much as does the type bar of a typewriter. Duplicate machines are used at each station connected into the network.

2

This machine also includes supports generally indicated at 1, on which a shaft or axle 3 is carried. Connected under the control of keys A, B, etc., by means of connections, generally indicated at 5, is a bank or set of contacts, generally indicated at 7. As shown, contacts 7 are mounted on a disc of insulation 9. Near the opposite end of shaft 3 is mounted a similar disc 11 having second set of contacts 13 carried thereby. Contacts 13 form the terminals of one end of the lines, generally indicated at 15.

On shaft 3 between discs 9 and 11 are mounted rotors or dual discs which are all substantial duplicates so that a description of one will suffice for all. Therefore, as seen in Fig. 2, dual discs may be described as comprising a cylindrical hub 17 to which are rigidly fastened perforated flanges 19 held on hub 17 as by end rings 21. These flanges 19 have the perforations 20 therein arranged in the shape of a circle adjacent the edge of the disc-shaped flange. Through these perforations extend headed contacts 23. Only two contacts 23 are shown in Figs. 1 and 2, the rest being omitted for the sake of clarity. Contacts 23 are slidable in the perforations and are stressed by compression springs 27 which are insulated from contacts 23 by discs 29 of insulating material. Springs 27 maintain contacts 23 in extended position and in contact with the adjacent contacts 23 or with contacts 7 and 13. Contacts 23 are connected together to form pairs of contacts which extend from the flanges 19 in opposite directions. These connections are made by the wires whose ends are represented in Figs. 1 and 2 as pigtails 25. These wires 25 are of varying length and connect contacts 23 which are not axially aligned, the connections being made in an irregular or heterogeneous. One circuit, for example that 35 under the control of key D, is illustrated in Fig. 1 and will be traced here as an example of all of these connections. From the connector 5^a under the control of key D, circuit is made to one contact 7^a which, in turn, engages a contact 23^a in the left hand flange 19 of the left hand of the three dual-discs shown in Fig. 1. From this contact 23^a, wire 25 leads to a contact 23^b in the right hand flange of the left hand dual-disc. The connections are shown from contacts 23 40 and wire 25 to a contact 13^a in the right hand end disc 11 whence a wire 15^a leads to an operating mechanism, for example QQ, in the receiving machine. Similar circuits extend between each pair of contacts 23 on each of the dual-discs and, therefore, circuits extend between each 45 50 55

one of the contacts 7 separately to one of the contacts 13. Each circuit is changed whenever one of the dual discs is rotated and these changes do not occur in any regular order so that an enormous number of different connections are possible.

End disc 11 is engaged by presser 31 which, in turn, is engaged by toggle-member 33 having pivotal connection to members 34 and 35. Member 34 engages support 1 while member 35 carries armature 37 of coil 39. Toggle members 33, 34, 35 are stressed by spring 41 so as to move in the opposite direction to that caused by energizing coil 39.

Selected keys, such as keys N, UVB and SB, in the embodiment shown, control switches 45, 47 and 49, respectively. One side of each of these switches is connected to a source of power such as battery 43. The other side of each of these switches is connected to coil 51, 53, and 55, respectively, which are associated with magnetic armatures carried respectively at the lower end of rods 57, 59, and 61, respectively. These armatures operate pawl mechanisms 63 which cooperate with ratchet mechanisms to rotate the dual discs each time one of the coils is energized.

Between the end discs 9 and 11 and the rotors or dual discs lying next to them, and between the adjacent rotors or dual discs, there are interposed springs 64 which stress the discs apart and consequently tend to separate the contacts carried by the discs.

The operation of my device is as follows: Switches 45, 47, and 49 are connected under the control of selected keys, in this instance keys N, UVB, and SB. This arrangement is made at each machine connected into the network. A message can then be sent by striking the keys A, B, etc., as the keys of a typewriter. If a selected key, such as N, is struck, switch 45 is closed and, therefore, coils 39 and 51 are energized, attracting armatures 37 and 59 and thus actuating toggle 33, 34, 35, and ratchet and pawl mechanism 63 respectively. Toggle mechanism 33, 34, 35 releases the rotors and allows springs 64 to cause the contacts carried by the discs to move out of engagement with each other. The selected ratchet and pawl mechanism 63 then rotates the rotors one step while the contacts carried by the rotors are disengaged. Release of key N, causes coils 39 and 51 to be deenergized and thus permits spring 41 to straighten toggle-members 33, 34 to clamp the rotors between the stators or end discs 9 and 11 and thus engage the contacts carried thereby in a new combination. The universal bar U. V. B. is operated every time any key is depressed. Hence, each time any key is depressed the magnet coil 39 is energized holding all contacts apart. Since the response of QQ is very fast, it gives indications before the contacts are separated by the high inertia apparatus 33, 34. Whenever no key is depressed, the contact tension is present. Thus, it will be seen that electro-magnet 37 and 39 is quick acting with respect to electro-magnets 51 and 57, 53 and 59, and 55 and 61. Another mode of operation would be to place spring 41 under compression rather than under tension as shown. Coils 39, 51, 53 and 55 would then be arranged to operate the mechanisms controlled thereby on the up stroke instead of on the down stroke, as shown in the drawings. In this modification, spring 41 normally holds the contacts 7, 23 and 13 dis-engaged. Electro-magnets 51 and 57, 53 and 59, and 55 and 61 would then be more quick in action than electro-magnet 37 and 39,

so that the dual-discs would be rotated before contact is closed through contacts 7, 23 and 13 by the energization of coil 39.

In Fig. 3 there is shown a modification of my device in which there is a block of insulation 65 located between the contacts 23 carried by the perforations in flanges 19. With rotors constructed in this manner, flexible contacts to cooperate with the contacts 23 are employed on the stators or end plates.

In Figs. 4 and 5 is shown another modification, in which hub 17, by means of end rings 21, carries flexible plates 67 on which are located contact points 68. Insulation is provided for contact points 68 as by insulating them from flexible plates 67 or by making flexible plates 67 or hub 17 and end rings 21 of non-conducting material. In this modification, the axial or endwise stress, tending to move the rotors and the contacts carried thereby to disengage position, is provided by springs similar to springs 64.

I claim:

1. In a system for secret communication, through a plurality of channels, a pair of end banks of electrical contacts forming the terminals of said channels, at least one of said end banks being axially movable, a pair of integrally-mounted rotary banks of electrical contacts, the contacts of each of said rotary banks being located for cooperation with the contacts of one of said end banks, connectors providing circuits between contacts of said rotary banks which are not axially aligned whereby rotation of said rotary banks selectively connects different sets of contacts, a motor having control of said rotary banks contacts to rotate them, an axially-movable device having control of said rotary banks and at least one of said end banks to move them axially to engage and disengage said contacts, and an interlock between said motor and said device whereby said rotation occurs during disengagement of said contacts.

2. In a system for secret communication, a pair of end banks of electrical contacts forming the terminals of channels, at least one of said end banks being axially movable, a pair of integrally-mounted rotary banks of electrical contacts, the contacts of each of said rotary banks being located for cooperation with the contacts of one of said end banks, connectors providing circuits between contacts of said rotary banks which are not axially aligned whereby rotation of said rotary banks selectively connects different sets of contacts, a motor having control of said rotary banks to rotate them, springs tending to separate said end banks from said rotary banks and to disengage said contacts, an axially-movable device having control of said rotary banks and at least one of said end banks to move them to engage and disengage said contacts, and an interlock between said motor and said device whereby said rotation occurs during disengagement of said contacts.

3. In a system for secret communication, a pair of end banks of electrical contacts forming the terminals of said channels, at least one of said end banks being axially movable, a pair of integrally-mounted rotary banks of electrical contacts, the contacts of each of said rotary banks being located for cooperation with the contacts of one of said end banks, connectors providing circuits between contacts of said rotary banks which are not axially aligned whereby rotation of said rotary banks selectively connects different sets of contacts, a motor having control of said

rotary banks contacts to rotate them, a toggle device having the axis of its arms which are movable into and out of alignment parallel to the axis of movement of said banks and having control of said rotary banks and at least one of said end banks to move said banks to engage and disengage said contacts, and an interlock between said motor and said device whereby said rotation occurs during disengagement of said contacts.

4. In a system for secret communication through a plurality of channels, a pair of end banks of electrical contacts forming the terminals of said channels, at least one of said end banks being axially movable, a pair of rotary banks of electrical contacts, the contacts of each of said rotary banks being located for cooperation with the contacts of one of said end banks, connectors providing circuits between contacts of said rotary banks which are not axially aligned whereby rotation of said rotary banks selectively connects different sets of contacts, a motor having control of said rotary contact banks to rotate them, an axially-movable device having control of said rotary banks and at least one of said end banks to move them to engage and disengage said contacts, and an interlock between said motor and said device whereby said rotation occurs during disengagement of said contacts.

5. In a mechanism adapted to transmit information by means of a number of circuits, a pair of end banks of electrical contacts forming parts of said circuits, at least one of said end banks being axially movable, a reel-shaped member having flanges confronting said end banks and having perforations in said flanges, contacts mounted in said perforations for axial movement therein and axial transportation thereby and cooperation with the contacts of said end banks, connections between pairs of said contacts mounted on said member which are not axially aligned whereby rotation of said member causes closure of different circuits between each pair of contacts at each engagement of said contacts, first means under the control of the operator and having engagement with said member to rotate it and to change the circuits which are closed, second means simultaneously under the control of the operator and causing axial movement of said member and at least one of said end banks to engage and disengage said contacts, and third means controlling the operation of said first and of said second means so that axial and rotary movement of said contacts cannot occur simultaneously.

6. In a mechanism adapted to transmit information by means of a number of circuits, a pair of end banks of electrical contacts forming parts of said circuits, at least one of said end banks being axially movable, a reel-shaped member having flanges confronting said end banks and having perforations in said flanges, contacts mounted in said perforations for axial movement therein and axial transportation thereby and cooperation with the contacts of said end banks, connections between pairs of said contacts mounted on said member which are not axially aligned whereby rotation of said member causes closure of different circuits between each pair of contacts at each engagement of said contacts, springs interposed between axially aligned pairs of contacts mounted on said member and stressing said contacts away from each other and towards engagement with the contacts on said end banks, first means under the control of the operator and having engagement with said member

to rotate it and to change the circuits which are closed, second means simultaneously under the control of the operator and causing axial movement of said member and at least one of said end banks to engage and disengage said contacts, and third means controlling the operation of said first and of said second means so that axial and rotary movement of said contacts cannot occur simultaneously.

10 7. In a mechanism adapted to transmit information by means of a number of circuits, a pair of end banks of electrical contacts forming parts of said circuits, at least one of said end banks being axially movable, a reel-shaped member having flanges confronting said end banks and having perforations in said flanges, contacts mounted in said perforations for axial movement therein and axial transportation thereby and cooperating with the contacts of said end banks, connections between pairs of said contacts mounted on said member which are not axially aligned whereby rotation of said member causes closure of different circuits between each pair of contacts at each engagement of said contacts, a block 15 of insulating material interposed between axially aligned pairs of contacts mounted on said member and tending to maintain said contacts in extended position for engagement with the contacts of said end banks, first means under the control of the operator and having engagement with said member to rotate it and to change the circuits which are closed, second means simultaneously under the control of the operator and causing axial movement of said member and at least one of 20 said end banks to engage and disengage said contacts, and third means controlling the operation of said first and said second means so that axial and rotary movement of said contacts cannot occur simultaneously.

25 8. In a cryptographic machine employing a plurality of circuits and means for connecting said circuits in a great number of various ways, a first set of contacts each forming a terminal of one of said circuits, a second set of contacts constrained to move along one path and each forming another terminal of one of said circuits, and a third set of bridging contacts constrained to move along another path at an angle to the path of said second set and each located so as 30 to bridge between one of said first set of contacts and one of said second set of contacts and shaped so that, upon movement of said third set of contacts along its path, the pairs of contacts which are bridged are successively varied, at least one 35 of said sets of contacts being movable to allow yielding engagement of said contacts upon movement of said second set of contacts along its path towards engaged position and to stress said sets of contacts towards disengaged position.

40 9. In a cryptographic machine employing a plurality of circuits and means for connecting said circuits in a great number of various ways, a first set of contacts each forming a terminal of one of said circuits, a second set of contacts constrained to move along one path and each forming another terminal of one of said circuits, a reel-shaped member having flanges thereon confronting said sets of contacts and having perforations therein and mounted so as to be constrained to move along another path at an angle to the path of said second set of contacts, and a third set of contacts comprising bridging contacts each mounted in one of said perforations for 45 slidable movement therein and connected together in pairs arranged so that, upon movement 50 55 60 65 70 75

of said third set of contacts along its path, the pairs of contacts which are bridged are successively varied.

10. In a cryptographic machine employing a plurality of circuits and means for connecting said circuits in a great number of various ways, a first set of contacts each forming a terminal of one of said circuits, a second set of contacts constrained to move along one path and each forming another terminal of one of said circuits, a cylindrical support of insulating material, and a third set of contacts mounted on said support for rotation and also for movement in the same direction as said second set of contacts and comprising flexible metal elements movable to engage and disengage the contacts of said first and of said second set of contacts and stressing each of said sets of contacts towards disengaged position and shaped so that, upon rotation of said support, the contacts of said third set successively bridge different pairs of contacts of said first and of said second set.

11. In a cryptographic machine employing a plurality of circuits and means for connecting said circuits in a great number of various ways, a first set of contacts each forming a terminal of one of said circuits, a second set of contacts constrained to move along one path and each forming another terminal of one of said circuits, a reel-shaped member having flanges thereon confronting said sets of contacts and having perforations therein and mounted so as to be movable along the same path as said second set of contacts and along another path at an angle thereto, a third set of contacts each mounted for slidable movement in one of said perforations and connected together in pairs arranged so that, upon movement of said third set of contacts along said other path, the pairs of contacts which are bridged are successively varied, and spring means provided between said pairs of third contacts and stressing said sets of contacts towards disengaged position.

12. In a cryptographic machine employing a plurality of circuits and means for connecting said circuits in a great number of various ways, a first set of contacts each forming a terminal of one of said circuits, a second set of contacts constrained to move along one path and each forming another terminal of one of said circuits, a reel-shaped member having flanges thereon confronting said sets of contacts and having perforations therein and mounted so as to be movable along the same path as said second set of contacts and along another path at an angle thereto, a third set of contacts each mounted for slidable movement in one of said perforations and connected together in pairs arranged so that, upon movement of said third set of contacts along said other path, the pairs of contacts which are bridged are successively varied, spring means provided between said pairs of third contacts and stressing said sets of contacts towards disengaged position, and insulating means interposed said pairs of third contacts and holding said pairs of third contacts in separated position.

13. In a cryptographic machine employing a plurality of circuits and means for connecting said circuits in a great number of various ways, a first set of contacts each forming a terminal of one of said circuits, a second set of contacts constrained for reciprocating movement and each forming another terminal of one of said circuits, a third set of bridging contacts constrained for rotation in a plane at an angle to the path of

5 reciprocation of said second set of contacts and each located so as to bridge between one of said first set of contacts and one of said second set of contacts and shaped so that, upon rotation of said third set of contacts, the pairs of contacts which are bridged are successively varied, springs interposed between said sets of contacts to allow yielding engagement of said contacts upon movement of said second set of contacts towards engaged position and to stress said sets of contacts towards disengaged position, a toggle device for reciprocating said second set of contacts, ratchet and pawl mechanism for rotating said third set of contacts, and an interlock between said device and said mechanism whereby said rotation can only occur when said contacts are in disengaged position.

10 14. In a system for secret communication through a plurality of channels, a pair of end banks of electrical contacts forming the terminals of said channels, at least one of said end banks being axially movable, a pair of integrally-mounted rotary banks of electrical contacts, the contacts of each of said rotary banks being located for cooperation with the contacts of one of said end banks, connecting means respectively providing circuits between contacts of the said rotary banks whereby rotation of said rotary banks selectively connects different sets of contacts, a motor having control of said rotary banks to rotate them, an axially-movable device having control of said rotary banks and at least one of said end banks to move them axially to engage and disengage said contacts, and an interlock between said motor and said device whereby said rotation occurs during disengagement of said contacts.

20 15. In a system for secret communication, a pair of end banks of electrical contacts forming the terminals of channels, at least one of said end banks being axially movable, a pair of integrally-mounted rotary banks of electrical contacts, the contacts of each of said rotary banks being located for cooperation with the contacts of one of said end banks, random connections between contacts of said rotary banks whereby rotation of said rotary banks selectively connects different sets of contacts, a motor having control of said rotary banks to rotate them, springs tending to separate said end banks from said rotary banks and to disengage said contacts, an axially-movable device having control of said rotary banks and at least one of said end banks to move them to engage and disengage said contacts, and an interlock between said motor and said device whereby said rotation occurs during disengagement of said contacts.

30 16. In a system for secret communication, a pair of end banks of electrical contacts forming the terminals of said channels, at least one of said end banks being axially movable, a pair of integrally-mounted rotary banks of electrical contacts, the contacts of each of said rotary banks being located for cooperation with the contacts of one of said end banks, connecting means providing circuits between contacts of said rotary banks whereby rotation of said rotary banks selectively connects different sets of contacts, a motor having control of said rotary banks contacts to rotate them, a toggle device having the axis of its arms which are movable into and out of alignment parallel to the axis of movement of said banks and having control of said rotary banks and at least one of said end banks to move said banks to engage and disengage said contacts,

and an interlock between said motor and said device whereby said rotation occurs during disengagement of said contacts.

17. In a system for secret communication through a plurality of channels, a pair of end banks of electrical contacts forming the terminals of said channels, at least one of said end banks being axially movable, a pair of rotary banks of electrical contacts, the contacts of each of said rotary banks being located for cooperation with the contacts of one of said end banks, connectors providing circuits between contacts of said rotary banks which are not axially aligned whereby rotation of said rotary banks selectively

connects different sets of contacts, an electro-magnet and its associated armature connected to said rotary banks of contacts to rotate them with step-by-step motion, an axially-movable device having control of said rotary banks of contacts and at least one of said end banks to move them axially to engage and disengage said contacts, and interlocking means between said electro-magnet and said device whereby said electro-magnet is energized to rotate said contacts while said device is actuated to cause disengagement of said contacts.

LEO ROSEN.
